UNITED STATES PATENT OFFICE.

WILLIAM B. FOSTER, OF UTICA, NEW YORK, ASSIGNOR TO FOSTER BROTHERS
MANUFACTURING COMPANY, A CORPORATION OF NEW YORK.

CORNER-FASTENING FOR BEDSTEADS.

1,021,185.

Specification of Letters Patent. Patented Mar. 26, 1912.

Application filed May 13, 1911, Serial No. 626,983. Renewed February 15, 1912. Serial No. 677,359.

To all whom it may concern:

Be it known that I, WILLIAM B. FOSTER, of Utica, in the county of Oneida and State of New York, have invented certain new and useful Improvements in Corner-Fastenings for Bedsteads; and I do hereby declare that the following is a full, clear, and exact description thereof, which will enable others skilled in the art to which it appertains to make and use the same, reference being had to the accompanying drawings, and to the reference-numerals marked thereon, which form part of this specification.

The purpose of my invention is to provide an improved device for fastening together at the corners the parts of a metal bedstead.

The advantages of my invention are simplicity in construction of the parts and ease of assembling the same, combined with great strength, permanence and rigidity. The small number of parts used in the construction and their simplicity obtain economy in manufacture. The parts are of such form that they do not need to be made with great exactness and yet produce a neat and highly efficient corner fastening of wide adaptability.

My invention is an improvement upon that form of corner fastening wherein a wedge has been used to draw the parts together by means of its being driven into a looped tongue which projects from one member through the other. This wedge construction was difficult to assemble and the wedge often worked loose.

Figure 1 is a perspective view of a bedstead corner embodying my invention, the sides of the corner post being partly broken away to better illustrate the construction. Fig. 2 is an elevation of the same from the end of the bed, with parts of the post and end rail broken away. Fig. 3 is a perspective view of the post block of Fig. 1. Fig. 4 is a horizontal sectional view through a round corner post and post block of correspondingly modified form. Fig. 5 is a horizontal sectional view on a reduced scale through a head or foot.

Referring to the drawing in a more particular description the corner post 6 may be of tubing of any desired shape, such as square, as shown in Figs. 1 and 2, or circular as shown in Fig. 4. At the proper height in the post 6, there is provided in its side an aperture 7 substantially horizontal

through which extends a tongue 8 projecting from the other or horizontal member which is to be secured to the post. This other member may be a post block 9 to which the side rail of the bed is to be detachably fastened by any desired means, such as by a tapering dovetailed joint of which only the tapering socket 10 upon the post block 9 is shown in the drawing, as that joint is not material to the subject matter of this invention; or the other member may be the end rail 11 of which there are usually two, connecting two corner posts 6 to form the head or foot of the bedstead.

The tongue 8 may be formed integral with the horizontal member as shown with the post block 9 or it may be the projecting end of a separate bar such as bar 12 extending into the end rail 11 and secured thereto as by screws 13. In either case the end of the horizontal member from which the tongue 8 projects forms a shoulder 14 of considerable area and of such form as to fit against the outer surface of the post 6 adjacent to the aperture 7.

The tongue 8 is provided with a U-shaped eye 15, having the rounding portion 16 toward the outer end of the tongue and the straight sides 17 extending back toward the horizontal member to a point nearly in line with the shoulder 14 thereon. The eye 15 extends through the tongue 8 in a vertical direction. Within the post 6 adjacent to the aperture 7 is preferably placed a reinforcing plate 18 having an aperture 19 substantially of the size of the aperture 7 and through this aperture 19 the tongue 8 projects into the interior of the post 6. The side of this plate toward the inner surface of the post is shaped to fit thereagainst as the purpose of the plate is to distribute over a greater area of the post 6 the pressure from the tapering screw 20 which is inserted through the eye 15 of the tongue 8 in place of the wedge heretofore used. One end of the tapering screw 20 is provided with any suitable means for rotating the screw, such for example as the squared head 21, shown in the drawings, which can be easily and securely engaged by a socket wrench having a shank long enough to reach down into the post.

After the tapering screw 20 has been inserted in the eye 15 of the tongue 8 and pushed down until it is in contact with the rounding side 16 of the eye on one side and

the reinforcing plate 18 on the other side, the screw is rotated in the proper direction to screw it down and its projecting threads 22 bite onto the rounding portion 16 of the 5 eye and onto the reinforcing plate 18 above and below the tongue with sufficient force to cause the tapering screw to be screwed down into the eye; and as it is so screwed down a larger part of the screw is gradually 10 brought into engagement with the eye, with the result, in an obvious manner, that the tongue 8 is drawn farther through the aperture 7 and the shoulder 14 of the horizontal member is drawn up against the outside of 15 the post 6 with great force. The tighter the members are so drawn together, the firmer becomes the hold of the contact parts upon the tapering screw and a very rigid fastening of the members is secured and one 20 that will not loosen with use or strain.

It will be noticed that the tightening of the joint is effected by the tapering form of the screw but that this taper is brought into use not by driving the screw straight down, 25 bodily as a wedge, but by rotating it. This method of applying power does not strain the parts as does the driving in of a wedge and yet a much tighter and more permanent joint is easily secured, as the power is applied with much greater leverage than in a 30 wedge of the same taper.

The reinforcing plate 18 is not necessary where tubing of sufficient thickness is used to withstand the strain but it is preferably 35 used with ordinary tubing which is strong enough for the general purpose of the bedstead but not strong enough to stand the local strain of such a tight joint.

The modification shown in Fig. 5 may be 40 advantageously used for the construction of the head or foot of a bedstead and consists in having the bar 12 with tongues 8 at each end, extend entirely through the end rail 11 without being secured thereto by any 45 means such as the screws 13. In this construction the longitudinal pull is not directly transferred to the end rail 11 but is kept in the bar 12 which draws together the posts 6 at each end until the end rail is 50 closely confined between the two posts.

Obviously permanent side rails may be

fastened to the post in the same way as the end rails 11, instead of using the post blocks 9 with detachable side rails. Where more than one of these fastenings are used in one 55 corner post, the lower one may be placed in position first and then the one next above and so on. On the other hand, on account of the security of the tapering screw when once tightened, some of them may be placed 60 in position from the lower end of the post, that is, with the larger end of the screw toward the bottom.

Any form of my corner fastening may be 65 easily and readily taken apart by rotating the tapering screw in a backward direction until it is loose enough to be withdrawn entirely from the eye, whereupon the tongue may be at once removed from the post.

What I claim as new and desire to secure by Letters Patent is:

1. In a corner fastener for bedsteads, a member having an aperture in its side, a second member having a shoulder adapted 75 to fit against said first member and a projecting tongue extending through said aperture, a recess in said tongue and a tapering screw adapted to be inserted in said recess and bear against the inside of said apertured 80 member on each side of said tongue and draw said shoulder against said first member upon rotation of said screw.

2. In a corner fastening for bedsteads, a post having an aperture in its side, a horizontal member having an eyed tongue projecting from its end through said aperture, a shoulder upon the ends of the horizontal member adapted to fit against said post, and a tapering screw adapted to be inserted 85 in said eye and bear against the inside of said apertured member and draw the horizontal member toward the post upon rotation of said screw.

In witness whereof I have affixed my 95 signature, in the presence of two witnesses, this 6th day of May, 1911.

WILLIAM B. FOSTER.
